his ATTORNEY.

UNITED STATES PATENT OFFICE.

WILLIAM J. O. ASTRUP, OF CLEVELAND, OHIO.

AWNNG-FIXTURE.

960,771.

Specification of Letters Patent.

Patented June 7, 1910.

Application filed January 14, 1909. Serial No. 472,239.

To all whom it may concern:

Be it known that I, WILLIAM J. O. ASTRUP, a citizen of the United States, residing at Cleveland, in the county of Cuyahoga and 5 State of Ohio, have invented certain new and useful Improvements in Awning-Fixtures, of which the following is a specification.

My invention relates to improvements in 10 awning-fixtures and, more particularly, to awning-brackets adapted to carry the awning-rod at the upper or stationary edge of the awning together with the necessary pulley-blocks in the equipment.

15 The primary object of the invention is to provide a generally improved fixture of this class which will be exceedingly simple in construction, cheap of manufacture and efficient in use.

20 Another object is to provide a "nutless" fixture of this class in which the various parts when assembled are so secured and arranged that they cannot become loose or disarranged and when the fixture is mounted 25 it may remain from year to year without the liability of rust interfering with the free and proper working of the curtain-rod clamping and fastening devices, said clamping and fastening devices being also de- 30 signed to be operated without the use of a wrench or other tool now required in connection with fixtures now in use employing nuts or similar mechanical expedients in their construction.

35 A further object is to provide a universal fixture, that is,—one which may be attached to horizontal or overhanging walls, as for example, an offset horizontal ledge of a porch or window as well as to vertical walls 40 or facings of similar structures.

With the above mentioned objects in view, the invention consists in the novel construction, arrangement and combination of parts, hereinafter described, illustrated in the ac- 45 companying drawings showing one of the embodiments of the invention, and particu- larly pointed out in the appended claims.

Referring to the drawings forming a part 50 of this specification, Figure 1, is a perspective view of an ordinary window-awning equipped with my improved fixture. Fig. 2, a plan view of one of the members or brackets of the improved fixture in its operative position as applied to the awning-rod con- 55 tained in the upper or stationary edge of the awning. Fig. 3, a central vertical sectional

view of the same. Fig. 4, a side elevation of the threaded boss portion of the improved fixture, together with attached interlocking rod-clamping member, and thumb screw for drawing said clamping member into clamping engagement with the awning rod.

Similar numerals of reference designate like parts throughout all the figures of the drawings.

The improved awning fixture is designed for the securing and supporting of the upper or stationary awning-rod containing edge of an awning, together with the necessary pulley-blocks in the equipment, and, 70 when applied to an ordinary window-awning may comprise two members or brackets suitably secured to the window frame as indicated in Fig. 1, of the drawings. Each member or bracket comprises a base or wall- 75 plate 1, provided with one or more forwardly-extending depending hooks 2. The wall-plate 1, provided with openings 3, for receiving and containing suitable attaching screws for the attachment of the fixture to vertical walls or facings of a window or 80 similar structure as illustrated in Fig. 1, terminates at its upper edge in an overhanging bracket member 4, preferably, provided with attaching ears 4^a, having screw openings 5. The overhanging bracket member 4, enables the fixture to be attached to an offset horizontal ledge of a porch or window where no convenient vertical wall or facing 85 is conveniently located for the purpose. 90

The base or wall plate 1, is provided with a threaded boss 6, terminating at its rear in an enlarged opening 6^a, at the rear of said wall plate. A thumb-screw 7, is mounted in the threaded opening of the boss, and when threaded therein in the act of assembling has its inner end upset or overturned forming an enlarged head or retaining stop 8, within the enlarged opening 6^a, and adapted to limit the outward or unscrewing movement of the thumb screw and thus prevent its loss by removal when the parts are assembled. The thumb screw is preferably formed of brass so as to guard against any liability of its rusting in the threaded boss and the head 100 of said thumb screw comprises an annular flanged shoulder portion 9, and an annular enlarged knurled head portion 10.

A depending rod-retaining clamping member 11, is mounted on the boss 6, and is provided with an opening 12, adapted to receive and contain the thumb screw 7, when the 110

parts are assembled. As a means for preventing the lateral movement of the clamping member when the parts are in their clamping position as shown in the drawings, the rear side of the head of the clamping member is provided with a retaining rib 13, adapted to normally interlock with a pocket-groove 14, on the face of the boss 6. The depending portion of the clamping member 10 extends downwardly above and in front of the nose portions of the depending hooks 2, and is preferably provided with a rearwardly-extending hooked portion 11^a, provided at its rear with a concave recess 11^b, 15 adapted to receive and contain the awning rod 15, when the latter is clamped by the improved fixture as shown most clearly in Fig. 3, of the drawings.

The throats of the depending hooks 2, are 20 adapted to receive and contain the eyes 16, of the pulley blocks 17, and the members or brackets of the improved fixture when mounted are adapted to remain from season to season.

25 By the construction shown and described it is obvious that the parts will remain assembled and when it is desired to place an awning in position the loosening of the thumb screw 7, will permit the depending 30 clamping member 11, to be swung to one side and the awning rod, together with the awning carried thereby, may be placed in position beneath the boss 6, and upon the nose portions of the depending hooks 2. The 35 clamping member 11, may then be turned down into its normal or clamping engagement with the front portion of the awning rod and the surrounding upper or stationary edge of the awning after which the 40 thumb screw may be drawn up to securely clamp the parts in their proper operative position as shown in the drawings.

Having thus described my invention, what I claim and desire to secure by Letters Patent is,—

1. In an awning-fixture, a wall-plate having an overhanging bracket member and provided with a boss having its threaded opening terminating in an enlarged opening at the rear of said wall-plate, said wall-plate having a pulley-hook having its nose extending forwardly and beneath the horizontal plane of said boss.

2. In an awning-fixture, a wall plate provided with a depending hook and a boss having a pocket-groove on its face and a threaded opening terminating in an enlarged opening, a thumb screw mounted in said boss and terminating in a retaining-stop in said enlarged opening, and a depending rod-clamping member carried by said thumb-screw and provided with a retaining-rib adapted to normally interlock with said pocket-groove on the face of said boss.

3. In an awning-fixture, the combination

with a wall-plate having a depending hook and a boss having a threaded opening terminating in an enlarged opening at the rear of said wall-plate; of a thumb-screw mounted in said threaded opening and terminating in a retaining-stop in said enlarged opening, and a rod-clamping member carried by said thumb-screw and extending downwardly above and in front of the nose portion of said depending hook.

4. An awning-fixture, comprising a wall-plate having depending forwardly-extending pulley-hooks and provided with a threaded boss having an enlarged opening at the rear of said wall-plate, a thumb-screw 80 mounted in said boss and having its end overturned in said opening forming a retaining stop, and a rod-retaining clamping member mounted on said boss by said thumb-screw and depending above and in front of 85 said pulley-hooks.

5. An awning-fixture, comprising a wall-plate provided with a threaded boss and an overhanging attaching bracket member, said wall-plate being provided with a plurality 90 of forwardly extending depending hooks, a depending rod-retaining clamping member mounted on said boss, and a thumb-screw taking through said clamping member and threaded into said boss.

6. An awning-fixture, comprising a wall-plate having a plurality of depending forwardly-extending pulley-hooks and an enlarged countersunk opening at its rear, an awning-rod carried upon the nose-portions 100 of said hooks, a thumb-screw mounted in said threaded boss and having its end upset in said enlarged countersunk opening forming a retaining stop, and a depending clamping member secured on said boss by said 105 thumb-screw and having its lower end abutting against the face of said awning-rod.

7. In an awning fixture, a base wall-plate terminating in a depending hook and provided with a forwardly extending portion 110 having a threaded opening extending therethrough, an awning-rod normally closing said depending hook, and a thumb-screw mounted in said threaded opening and provided with a head and an awning-rod 115 engaging member.

8. An awning fixture, comprising a base provided with a head having a threaded opening and terminating in a depending hook, an awning-rod normally resting beneath said head and closing said hook, and a thumb-screw mounted in said threaded opening and provided with a head carrying an engaging member at its base.

9. An awning fixture, comprising a base member having a pulley-hook and provided with a head having a threaded opening terminating in an enlarged opening, and a thumb-screw member mounted in said threaded opening and having its end upset 125 130

in said enlarged opening forming a retaining stop, said base member having a rod receiving recess intermediate said head and pulley-hook, and said thumb-screw member 5 having a head and an awning-rod engaging member.

10. An awning fixture, comprising a base terminating in a depending hook and provided with a head having a threaded open-
10 ing passing therethrough, an awning-rod interposed between said head and hook and normally closing the latter, and a thumb-

screw mounted in said threaded opening and having its end upset forming a retaining stop at the rear of said threaded opening, 15 said thumb-screw being also provided with a head and an awning-rod engaging member.

In testimony whereof, I have affixed my signature in the presence of two witnesses.

WM. J. O. ASTRUP.
